UNITED STATES PATENT OFFICE.

VIOLA GALLUP, OF NEW YORK, N. Y., ASSIGNOR TO WALTER B. GALLUP, OF NEW YORK, N. Y.

DESIGN FOR AN AIRPLANE VISOR CAP.

Application filed July 27, 1928. Serial No. 27,601. Term of patent 3½ years.

To all whom it may concern:

Be it known that I, VIOLA GALLUP, a citizen of the United States, and residing in the county of New York, city of New York, and State of New York, have invented a new, original, and ornamental Design for an Airplane Visor Cap, of which the following is a specification, reference being had to the accompanying drawings forming a part thereof.

The figure is a view, in perspective, showing the visor in the outline of an airplane.

I claim:

The ornamental design for an airplane visor cap as shown.

This specification signed this 3rd day of July 1928.

VIOLA GALLUP.
